UNITED STATES PATENT OFFICE

JEROME W. HURYCH, OF ASTORIA, NEW YORK, ASSIGNOR TO HAMILTON MANUFACTURING COMPANY, OF TWO RIVERS, WISCONSIN, A CORPORATION OF WISCONSIN

DRAFTING TABLE

Application filed November 21, 1928. Serial No. 320,925.

The present invention has reference to a drawing board and appertains more especially to an adjustable support therefor.

The main object of this invention is to produce an improved support of the character described, capable of being placed in desired position by one hand of the operator whose foot controls the release of an automatic locking mechanism.

10 Another object is the production of a support of the nature set forth wherein the table is so nicely overbalanced as to slowly lift or rise when liberated, but which can be depressed or moved into changed position by 15 a slight pressure of the operator's hand.

A further object is to provide a support of the class mentioned with an arrangement of levers the ends whereof on opposite sides of a common pivotal axis are connected with the 20 table and a counterweight in such a manner as to maintain perfect equilibrium therebetween in all positions.

Still another object consists in producing a support of the kind referred to, having 25 paired levers forming with the table and counterweight, the sides of flexibly jointed, oppositely disposed parallelograms, maintaining equipoise between the aforesaid elements.

30 A still further object resides in providing a support of the type specified with sets of levers coupled by their corresponding opposite ends to the table and its counterweight, which levers serve to control the vertical and horizontal movements of the table.

An additional object is the provision in a support of the species implied, of separate locking means for each set of levers controlling the table's vertical and horizontal movements so as to enable independent adjustments thereof.

A general object is to supply a support for the purpose in view which shall be of strong and rigid construction; void of costly and 45 complicated parts; readily assembled; convenient to adjust into different positions and firmly locked therein; besides, amenable to economical manufacture.

Other objects and advantages of the invention will in part be obvious and in part be

more fully brought out in the detailed description hereinafter contained.

The invention consists in the various combinations and sub-combinations of elements, arrangements and interrelative disposition 55 of parts, and peculiar features of construction pertaining to the improved support, as herein described and defined in the appended claims.

A practical embodiment of the invention 60 is illustrated in the drawings hereto annexed and wherein:—

Figure I is a side view of this improved drafting table support, looking at the same from left to right according to Fig. III;

Fig. II is a section on the line II—II of Fig. III, looking thereon in a direction from right towards the left;

Fig. III is a front view, looking towards the left from the right hand side of Fig. I, 70 parts being broken away;

Fig. IV is an enlarged fragmentary elevation, partly in section, of a detail appearing in the middle portion at the left hand side of Fig. III;

Fig. V is also a fragmentary elevation, partly in section, of a detail appearing in the lower and middle portion at the left of Fig. III;

Fig. VI is an enlarged, fragmentary section, taken on the line VI—VI of Fig. III, 80 looking downwardly thereon;

Fig. VII is also an enlarged fragmentary section, taken on the line VII—VII of Fig. III, looking in an upward direction thereon; and

Figs. VIII—IX are diagrammatic side-views corresponding in outline to Fig. I, showing some of the various positions in which the drawing board may be placed.

Briefly described, the invention as it exists in the embodiment thereof herein exemplified, comprises spaced apart legs adapted to stand on a floor. In and between these legs or stands is rotatably supported a solid 95 shaft to the outer free ends of which are fastened double-armed levers. The opposite terminals of the latter are pivotally connected to a part on the drafting table and to a rod whereon is hinged by their upper portions a 100

couple of counterweights. A tubular shaft is revolvably carried by the solid shaft intermediately of the before named floor stands. In proximity to these stands are secured to the hollow shaft another set of levers angularly offset with respect to the ones first mentioned. The second set of levers have their terminals coupled up by means of links to the table and to the lower portions of the aforesaid counter-weights. Both sets of levers, located on opposite sides of one of the stands, are provided with semi-circular racks engaged by spring urged detents, serving to retain the racks and the thereto attached levers in predetermined positions. Foot actuated pedals joined thru the agency of flexible connections to the detents, are capable upon being depressed of retracting the same when it is desired to change the interrelative adjustments of the levers and the thereon depending inclination as well as height of the drafting table.

Obviously, the greatest benefit will be derived from the invention by using it in its entirety after the manner hereinabove expressed, altho it may be noted that an operative support of acceptable design may be produced by employing a less number of parts with correspondingly diminished advantages. Further it will be observed by experts familiar with inventions of analogous import, that the combined double sets of levers direct and indirectly connected to the drafting table and to the counterweights, as well as the detent releasing mechanism herein disclosed, are susceptible of various modifications having the same end in view. Therefore, let it be understood, that the annexed drawings are offered by way of example only, and are not put forth as representing the sole means of reducing the invention to practice.

As illustrated on the said drawings, the support constituting the present embodiment of the invention includes preferably two stands, right and left, 11, 11a, respectively, having basal portions 12, 12a, adapted to rest in spaced apart relation on a floor surface A. These stands or uprights as they may also be termed, are substantially alike, except that the one (11a) on the left hand side of Fig. III, is provided with bearing bosses disposed at different elevations above the floor, for a purpose that will more fully appear later on. The upper and rounded portions of stands 11, 11a, are formed with bearings 14, 14a, respectively, wherein is rotatably supported a shaft 15 which by preference is of the solid type. To the free, opposite terminals of this shaft is secured, as by keying, a pair of levers 16 having central hubs 60 which are held in offset relation to the outer faces of bearings 14, 14a, by spacing collars 17 interposed therebetween. Intermediately of the inwardly turned faces of the last named bearings, is revolvably carried about the shaft 15, another but hollow shaft 19. Levers 20

have their hub portions affixed to the tubular shaft 19 by keys or other appropriate contrivances.

It will be observed with particular reference to Figs. I, II and III of the accompanying drawings that both sets of the levers 16 and 20 are composed of un-equal arms (16)—16a and (20)—20a, respectively. Of these arms, it is to note, that the ones designated 20a are longer than lever arms 16a. The outer ends of the longer arms (16) of the first mentioned set of levers are pivotally connected by means of brackets 22 to the lower forward portions of bar-like cleats 23 which may serve as backing strips reinforcing the drafting board or table B, or to any other parts to which the latter may be attached. Thru the same ends of the shorter arms 16a of the identical levers, is passed a rod 24 whereon is hinged by their upper portions one or more counterweights 25, generally a pair thereof, depending upon the size and heaviness of the table to be balanced. The corresponding ends of the other arms (20) pertaining to the second set of levers 80 are flexibly coupled to brackets 22a similar to those first named, by links 26. Said second set of brackets 22a are attached to the aforesaid parts 23, altho to the reverse sides thereof, with respect to the brackets 22, 90 previously referred to. The shorter arms 20a are jointed in a like manner, but individually or by separate pivot pins 27 to the adjacent lower portions of the counterweights 25, thru the agency of shorter links 28. It will be understood, that for a rather narrow or light-weight table, when only one counter-balance is needed, both of the links 28 can be movably connected thereto. Obviously, for very small boards or easels, the employment of 100 single links 26 and 28 is contemplated. If desired, the weights may be built up of plate-like sections 25a held together by bolts 25b, admitting of additional laminæ being included in the assemblage thereof to increase 105 the weight.

From the foregoing it will be seen that around the bearings of each of the floor stands, there is mounted to oscillate, in planes parallel with the sides thereof two sets of different size parallelograms. The larger ones of the latter, consist of the longer arms (16)—(20) and links 26, strips 23 closing these parallelograms intermediately of the pivot-brackets 22—22a. On the opposite side of the concentric shafts 15—19, the smaller parallelograms include the shorter arms 16a—20a, links 28, and the counter-weights, the distance between the pivots 24—27 thereof, completing the last named parallelograms. By virtue of the reason that the arms 16a—20a being of considerably shorter lengths than the other set of arms (16)—(20) so as to reduce the space occupied in rear of the stands 11—11a by the weights 25, the same are there- 130

fore made correspondingly heavier in comparison with the drafting board or table. In practice, it is desirable to proportion these weights so as to be slightly heavier than said table in order that it may have a tendency to lift or move slowly upward when liberated or unlocked.

The means for locking and unlatching the aforesaid major and minor parallelograms incidental to altering their shapes coincident with changing the positions of the table B, comprises in the present embodiment of the invention, semi-circular racks 30, 31. For the sake of convenience, said racks may be formed as integral extensions to the under and rear edges of the arms (16)—16a and (20)—20a, respectively. These segmental appendages which by preference are disposed only at one side of the table, e. g. at the left hand stand 11a, are provided with rounded teeth 30a, 31a, arranged concentrically with relation to the levers' common pivotal centre about the axis of shaft 15. Detents on the order of studs 32, 33 adapted to enter between the teeth or dentations 30a, 31a sidewise, hold racks 30, 31, respectively, from being swung one way or the other, when in engagement therewith. Studs 32, 33, as most clearly seen from Fig. VII, extend from the sides of the latch-levers 34, 35, affixed as by pinning them to spindles 36, 37, respectively. These spindles are journalled in bearing bosses 38, 39, projecting in a front and rear direction from the left hand stand 11a, a given distance below the thereto appertaining upper bearing 14a, being as shown, disposed on a horizontal line substantially tangential to the periphery of the said racks. The aforementioned latch-levers and detent studs are urged automatically upward against the rack dentations. The instrumentality performing this function may consist as illustrated, of a single resilient element in the nature of a contractible spring 41. The latter can expediently be anchored by its extremities to eyes provided in the ends of ears 42, 43 that depend from the underside of a separate hub 44 and from the hub of the latch lever 35 respectively. The means for individually retracting the latch-levers in order to release the curved racks, may be composed of cables, chains or other yielding mediums, depicted by dot-and-dash lines 46, 47, in Figs. I to V. As represented, the last named connections are attached to eyes formed in ears 48, 49 (Figs. I and VII). Of these ears, the one denoted 48, reaches downwardly from the lower side of the latch-lever 34, while the other ear 49 is provided as an adjunct to the latch lever 35. Fixed to spindle 37, at the end thereof opposite to the lever 35, is a collar 50 maintaining it in axial alignment.

The cables spoken of, are passed over individual sheaves 52, 53 revolvably mounted on opposite sides of the stand 11a upon a stud or bolt 55 supported in any suitable manner

therein. With the lower front part of the base 12a of the said stand, is formed a bearing boss 56 wherein is carried a stub shaft 57 having pedals 58, 59 loosely mounted on the outer ends thereof. Said pedals which have 70 reversely offset foot rests 58a, 59a, may be maintained in their axial alignment, by cotter pins with interposed washers, as most clearly represented in Fig. VI. At the rear portions of pedals 58, 59, the same are formed or connected with arms 60, 61 provided with ears to which are fastened the lower terminals of the flexible mediums 46, 47 respectively. The latter as before stated, control the latch-levers 34—35, dentated segments 30—31, and the conjoined arms (16)—16a and (20)—20a, that directly and indirectly engage the table B and weights 25, respectively. For the purpose of locating the afore-named pedals in the most advantageous positions, i. e. within reach 85 of the operator's feet, there is cast or otherwise attached to the outer and inner faces of the basal portion of the stand 11a, stops 62, 63, disposed in the arcuate paths followed by arms 60, 61 respectively. The stops referred to serve to limit the rearward and upward swinging movements of the said arms and the therewith associated pedals 58, 59 respectively. From the foregoing description it will be comprehended that at such times as a draftsman seated by table B, places both feet on the pedals, thus releasing the two racks 30, 31, the table will rise or lift due to the preponderance of the weights 25 acting thereagainst. If only the left hand pedal 58 is depressed, retracting the latch lever 34 from the dentations 30a, the double-armed levers 16 on the central shaft 15 become liberated for an up and down adjustment of the drafting table's front edge. If on the other hand, the right pedal 59 alone is pushed down, it is the second set of levers 20 on the tubular shaft 19, which are released, and may at option have their positions changed to shift the drawing boards' upper edge in a front and rear direction. By reason of the fact all connections of the levers with the table and weights as well as the detent mechanism, are pivotal, the friction therebetween is so slight 110 that the mere touch of a person's hand suffices to effect every change desired. Immediately one or both feet are removed from the pedals, the latch levers under influence of spring 41 reset themselves in engagement with the segmental racks without any other tightening means being needed. The draftsman's hands are always free to manipulate the table and to manage those of his implements or instruments generally reposing thereon. All of 115 the above enumerated features contribute in making the support under consideration highly desirable in the saving of time required for the adjustment as well as in the use thereof, besides the comfort and avoidance of cramped positions or stretching, it 120 125 130

affords the draftsman working at a board mounted on a support constructed in accordance with the description hereinbefore contained. Some of the various positions in which this counterbalanced table may be placed, is illustrated by Figs. VIII and IX. As therein shown, the same elements to the ordinals whereof has been added suffixes, denote corresponding positions of the table and the counterweight. From these views it will be apparent that either short or tall persons may use the table or work at the upper and lower edges thereof with equal convenience.

In its broader aspects, the invention herein disclosed is not limited to the precise features of construction and arrangement of parts shown and described, nor to the particular structural make up or design by which it can be reduced to practice, as numerous changes may be made in the details without departing from the principles of the invention, or even sacrificing any of its chief advantages.

Having now described my invention, what I claim as novel therein and desire particularly to protect by Letters Patent of the United States, is:—

1. A support for drawing tables and the like, including levers independently pivoted in crossed relation one to the other about a common axis, a table attachment part and a counter-weight flexibly connected near the opposite extremities to one of said levers, and links flexibly coupling the corresponding ends of the other lever to said part and said weight.

2. A support for drawing tables and the like, including levers mounted for inter-relative rotation, links flexibly joined to one of said levers forming therewith and with the other lever three sides in each of oppositely disposed parallelograms, a table attachment part forming the fourth side of one of said parallelograms and a counter-weight completing the other of said parallelograms, and means pivotally connecting the levers and said links with the last named elements thereby completing said parallelograms.

3. A support for drawing tables and the like, including separate levers pivoted inwardly of their ends in offset relation thereto about a common centre to provide longer and shorter portions, a table attachment part and a counter-weight respectively connected to the longer and shorter portions of one of said levers, links similarly connecting the corresponding portions of the other lever with said attachment and counterweight, and mechanism for independently locking the said levers in adjusted positions.

4. A support for drawing tables and the like, including a table attachment part and a counterweight, levers and links pivotally connected up with said part and said weight forming on both sides of a common centre,

oppositely disposed closed parallelograms maintained in constant equipoise, members carried by each of said levers, pivoted elements coacting with said members to hold said levers locked, and means for oscillating said elements to release the levers when changing the position of the said table part.

5. A support for drawing tables and the like, including a stand, levers pivoted independently of one another at opposite sides of said stand, a table attachment part and a counterweight direct connected to the opposite outer ends of one of said levers, links coupling one extremity of the other lever to said part, and other links connecting said weight with the opposite end of the last mentioned lever.

6. A support for drawing tables and the like, including a table attachment part and a counterweight, levers pivotally supported in crossed relation independently of one another, one of said levers having its extremities connected directly to the lower and upper portions of said part and said weight respectively, and links connecting the corresponding ends of the other lever to the opposite portions of the part and the counterweight respectively, the connections of said lever and said links with the last named elements being spaced at distances apart equaling the effective length of the link connected lever.

7. A support for drawing tables and the like, including a table attachment part and a counterweight, a pair of brackets attached to said part, a lever pivoted intermediate its ends directly connected by said ends to one of said brackets and to a part on said weight, and another lever similarly mounted and flexibly connected at its ends respectively with the other bracket and a different part of the said counterweight.

8. A support for drawing tables and the like, including floor stands spaced one from the other, a shaft having its bearings in said stands projecting therebeyond, a set of levers fastened to the projecting portions of said shaft, a tubular shaft mounted to revolve around the latter intermediately of the stands, another set of levers secured to said tubular shaft in proximity to the said stands, a table attachment part and a counterweight, means coupling said first set of levers direct with said part and said weight, and other means indirectly connecting said second set of levers with the last named elements.

9. A support for drawing tables and the like, including a pair of floor stands, a shaft journalled therein extending beyond the same, a tubular shaft revolvable around said first shaft intermediately of said stands, a table attachment part and a counterweight, a set of levers affixed to the extending portions of the first mentioned shaft connected directly to said part and said weight, another

set of levers secured to the ends of said tubular shaft coupled indirectly to the last named elements, coacting members carried by one of the stands and one of each of both sets of levers capable of holding the latter locked in various positions, and pedals controlling the release of the stand carried members.

10. A support for drafting tables and the like, including a pair of stands, a main shaft rotatably carried by said stands, a set of levers affixed to said main shaft, a hollow shaft revolvably mounted upon the latter, a set of levers secured to said hollow shaft, a table attachment part and a counterweight, means 15 flexibly connecting adjacent ends of the hollow shaft levers with said part, means flexibly connecting adjacent ends of the main shaft levers with the said part and spaced from the hollow shaft lever connection therewith, 20 with, means flexibly connecting opposite ends of said hollow shaft levers with said counterweight, and means flexibly connecting the opposite ends of said main shaft levers with said counterweight in spaced relation to the 25 hollow lever connection therewith.

11. A support for drafting tables and the like, including floor stands, a main shaft rotatably carried in said stands, a set of lever arms affixed to said main shaft, a hollow shaft 30 independently revolvable around the latter, a set of lever arms secured to said hollow shaft, a table attachment part and a counterweight, means flexibly connecting adjacent ends of the hollow shaft arms with said 35 part, means flexibly connecting adjacent ends of the main shaft arms with the said part and spaced from the hollow shaft arm connection therewith, means flexibly connecting the opposite ends of said main shaft arms with said 40 counterweight in spaced relation to said hollow shaft arm connection therewith, means associated with one of the stands for independently locking each shaft, and separate foot operated means controlling each of said 45 locking means to release either of said shafts.

12. In a drafting table support, a pair of levers arranged in crossed relation and pivoted about an axis common thereto, a table part and a counterweight, one of said levers 50 being flexibly connected at its ends respectively with end portions of said part and counterweight, links coupling opposite extremities of the other of said levers with other end portions of the said part and counterweight and spaced from the connections of the first lever therewith, and locking means 55 for each of the said levers.

JEROME W. HURYCH.
